UNITED STATES PATENT OFFICE.

JEFFERSON S. STEPHENS, OF WASHINGTON, PENNSYLVANIA.

ROTARY ENGINE.

SPECIFICATION forming part of Letters Patent No. 600,240, dated March 8, 1898.

Application filed April 15, 1897. Serial No. 632,320. (No model.)

To all whom it may concern:

Be it known that I, JEFFERSON S. STEPHENS, a citizen of the United States, residing at Washington, in the county of Washington 5 and State of Pennsylvania, have invented certain new and useful Improvements in Rotary Engines; and I do hereby declare the following to be a full, clear, and exact description of the invention, such as will enable others skilled in the art to which it 10 pertains to make and use the same.

This invention relates to rotary engines, and has for its object to provide in connection with a rotating cylinder two or more pistons carried thereby and adapted to contact with the inner side of a stationary cylinder throughout nearly the entire inner surface of said stationary cylinder, thereby increasing the effectiveness and power of the engine.

20 The improved engine is adapted to be run either by steam, water, or any other fluid or liquid under pressure.

The detailed objects and advantages of the invention will be pointed out in the course of 25 the subjoined description.

The invention consists in a rotary engine embodying certain novel features and details of construction and relative arrangement of parts, as hereinafter fully described, illustrated in the drawings, and incorporated in 30 the claims hereto appended.

In the accompanying drawings, Figure 1 is a vertical section through a rotary engine constructed in accordance with the present 35 invention. Fig. 2 is a vertical transverse section through the same. Fig. 3 is a detail perspective view of the revolving cylinder. Fig. 4 is a plan view of the packing or following head. Fig. 5 is a perspective view of 40 the removable head of the inner rotating cylinder. Fig. 6 is a detail perspective view of the eccentric-straps, showing also the pistons carried thereby. Fig. 7 is a cross-section through the eccentric-straps, showing their 45 tongue-and-groove engagement. Fig. 8 is a detail longitudinal section through the steam-chest, showing the slit-valve. Fig. 9 is a detail elevation of a portion of one side of the engine, showing the reversing-lever.

50 Similar numerals of reference designate corresponding parts in the several views.

Referring to the drawings, 1 designates the

main body of the engine, which is substantially in the form of a cylinder, having a broad base 2, hollowed out upon its under 55 side, as indicated at 3, to make room for the heads of the screws or bolts whereby the piston-seat is adjusted.

Extending through the stationary cylinder or body 1 is a main driving-shaft 4, which is 60 mounted in the heads of the stationary cylinder and in bearings secured thereto and also in bearing-standards 7, located upon each side of the engine and at a distance therefrom, which will permit the removable head 5 of the 65 stationary cylinder to be detached for giving access to the interior thereof when necessary. Mounted fast upon the shaft 4 is a fly-wheel 6, and this shaft may also have mounted fast thereon a band-pulley, through which power 70 may be transmitted from the engine to the machine to be driven.

8 designates the inner revolving cylinder which carries the pistons 9, the cylinder 8 being provided at diametrically opposite points 75 with peripheral radial recesses 10, into which the pistons slide in radial lines. The cylinder 8 is also provided in its periphery with openings 11, which communicate with the recesses 10 under the pistons 9, so as to normally force said pistons upward against the inner surface of the stationary cylinder 1, thereby preserving a close contact between said parts and preventing the same from passing between the pistons and stationary cylinder. 85 The pistons 9 are provided with inwardly-extending and radially-disposed stems 12, which carry at their inner ends rectangular and substantially square eccentric-straps 13, having open centers and provided upon their opposite or outer sides with reversely-disposed flanges 14, the purpose of which will hereinafter appear. The stem 12 is provided at one end with a right-hand thread and at the opposite end with a left-hand thread, so that by turning said stem in one direction the strap 13 and piston 9 will be forced apart, while by turning the stem in the opposite direction the said parts will be drawn closer to each other, thus enabling the proper contact to be had between the piston 9 and the inner surface of the stationary cylinder. One of the straps 13 is provided upon 90 its inner surface with ribs or tongues 15 and

the other strap is provided upon its abutting surface with grooves 16 to receive said ribs, thus causing the two straps to maintain the proper relation to each other while allowing them to slide freely in opposite directions. The straps 13 are arranged within the open center 17 of the rotating cylinder 8. The cylinder 8 is provided at one side with a fixed or stationary head 18 and at the opposite side 10 with a removable head 19 for giving access to the straps 13, and both heads are provided with recesses 20 to receive and permit the movements of the pistons 9.

Surrounding the shaft 4 is a stationary cam 21, which is arranged in a position adapting it to act against the inner surfaces of the straps 13. Arranged at one side of the cam 21 is a stationary collar 22, between which and the cam operates one of the flanges 14 of 20 the straps 13. At the opposite side of the cam is a stationary hub or collar 23, between which and the cam operates the other flange 14 of the remaining strap 13. The cam 21 and the collars 22 and 23 are all formed with 25 alining openings to receive a rod or shaft 24, which passes through said parts and also through the fixed head of the stationary cylinder, thereby securely holding said parts and preventing their rotation. The inner 30 edge of the flange 14 of each strap 13 when in its uppermost position bears upon the upper rod or shaft 24, and when reversed or in its lowermost position it bears against the under side of the main shaft 4. At all times 35 the flange 14 is practically out of contact with both of said shafts, and the position of the piston is influenced and controlled by the engagement between the inner surface of the strap 13 and the cam proper, 21. At the lowest 40 point of the throw of the pistons said pistons come in contact with a transverse seat 25, arranged at the bottom of the stationary cylinder. By means of the particular construction of the cam and the arrangement 45 of the shafts 4 and 24, taken in connection with the form of the straps 13, the pistons 9 contact with the inner surface of the cylinder soon after leaving the seat 25, thus making said pistons effective during the greater 50 portion of their stroke. On each side of the seat 25 are seat extensions 26, which insure the lifting of the pistons 9 for causing them to pass onto the seat 25 and preventing them from catching against the edges of said seat 55 and thus stopping the engine.

Outside of the removable head 19 of the inner cylinder is a backing-head 27, which fits closely within a stationary cylinder and is provided with a recess or notch 28 to fit over 60 the seat 25. The head 27 is free to slide inward and is forced into close contact with the inner cylinder by means of a screw-sleeve 29, which screws into an opening 30 in the outer removable head of the stationary cylinder and in which the main shaft 4 is mounted. The stationary head 18 of the inner cylinder is provided with detachable rings 31, which

take the wear of the inner cylinder and which when they become worn out may be readily removed and replaced by new ones at a trifling 70 cost, thus increasing the durability and life of the engine. The same expedient may be resorted to at the opposite side of the inner cylinder and at other points where excessive wear occurs.

75 The seat 25 is mounted in a mortise or recess 32 in the base 2, so that it may be moved up and down. Extending through the bottom of the base 2 are five bolts—a central bolt or tap-screw 33 for effecting a raising and 80 lowering of the adjustable seat 25, and other bolts or tap-screws 34, which have a threaded engagement with the sliding seat for holding the latter fixed in its adjusted position. This renders it possible to produce a close contact 85 between the pistons and seat and to compensate for wear.

Upon the outside of the removable head 5 is located a steam-chest 35, having supply-ports 36, which extend through the head 5 90 and base 2 and communicate with the interior of the stationary cylinder at the points 37 at each side of the seat 25, so that when steam is admitted through one of said ports it will drive the engine in one direction and 95 when admitted at the other side it will drive the cylinder in a reverse direction. Intermediate the supply-ports 36 is an exhaust-port 38, which communicates with an exhaust-opening 39 in the base 2 leading to the opposite side of the engine or any convenient point.

100 40 designates a slide-valve which is hollow upon one side, as indicated at 41, and which is of sufficient length to simultaneously cover one supply and the exhaust port when slid in one direction and when slid in the opposite direction to cover the exhaust-port and the remaining inlet-port while opening the other supply or inlet port. The valve 40 is 105 provided at one end with a rod or stem 42, which extends through a stuffing-box in one end of the chest, where it connects with a reversing-lever 43, mounted upon the body of the engine at one side.

110 Stuffing-boxes may be provided in the inner cylinder, through which the stems 12 of the eccentric-straps and pistons pass, and at other points wherever a tight joint is needed.

115 From the foregoing description it will be 120 seen that a very simple, compact, and effective rotary engine is provided and that the same may be run either by steam or other suitable agent.

125 Suitable provision may be made for oiling the operative parts of the engine wherever friction occurs, and other changes in the form, proportion, and minor details of construction may be resorted to without departing from the principle or sacrificing any of the advantages of the invention.

130 Having thus described the invention, what is claimed as new is—

1. In a rotary engine, a stationary cylin-

der, a rotary cylinder mounted therein and mounted on a revolute shaft journaled in the head of the stationary cylinder, in combination with a stationary cam surrounding the main shaft, stationary collars arranged at each side of said cam and spaced apart therefrom, a rod or shaft arranged parallel to the main shaft and extending through said cam and collars and connecting the same rigidly to one head of the stationary cylinder, radially-movable pistons carried by the inner cylinder, and straight-sided eccentric-straps connected to said pistons and surrounding said cams and also having flanges which enter between the cam and stationary collars on the main shaft, substantially as described.

15 2. In a rotary engine, a stationary cylinder,

der, a rotary cylinder mounted therein, a rotating shaft upon which the cylinder is fast, radially-movable pistons carried by the rotating cylinder and operating in a diametrical line, a stationary cam surrounding the main shaft, and rectangular eccentric-straps connected to said pistons and having a tongue-and-groove engagement upon their inner 25 abutting surfaces, substantially as described.

20 In testimony whereof I have signed this specification in the presence of two subscribing witnesses.
